LIQUID DIVIDING FEED MECHANISM

Adolf von Wangenheim and Walter S. Landon,
Detroit, Mich., assignors to Detroit Lubricator
Company, Detroit, Mich., a corporation of
Michigan

Application May 14, 1934, Serial No. 725,664

7 Claims. (Cl. 184—7)

The invention relates to liquid feeding mechanisms more particularly designed for use in connection with lubricating systems and it is the object of the invention to accurately divide the liquid which is being fed into a plurality of accurately measured portions and to deliver the same to separate conduits. To this end the invention consists in the construction as hereinafter set forth.

10 In the drawings:

Fig. 1 is a plan view of the device;
Fig. 2 is a side elevation thereof;
Fig. 3 is an end elevation;

Fig. 4 is a cross section on line 4—4 of Fig. 1
15 viewed in the direction of the arrow;

Fig. 5 is a similar view viewed in the opposite direction as indicated by the arrows 5—5, Fig. 1;

Figs. 6, 7, 8 and 9 are diagrammatic views illustrating the successive operations in measuring, 20 dividing and feeding the liquid to the separate delivery conduits;

Figs. 10, 11, 12, 13, 14 and 15 are elevations respectively of the six sides of the casing;

Figs. 16, 17, 18, 19, 20, 21, 22 and 23 are cross sections taken on lines of corresponding number in the elevations, Figs. 10 to 15.

Fig. 24 is a diagram illustrating a plurality of dividing units used in combination.

Generally described, our improvement comprises a casing preferably formed of an integral casting which is provided with an inlet for the liquid to be divided and a plurality of outlets for the divided portions of the liquid. Intermediate said inlet and outlets the casing is further provided 30 with a plurality of cylindrical recesses, each containing a reciprocating plunger which functions as a double-headed piston and a valve. The casing is further provided with ports and passages so arranged that in one position of each plunger 35 the valve portion thereof will connect the cylinder for another plunger with one end to the inlet and its opposite end to one of the outlets. This will result in the movement of the plunger in the latter cylinder by pressure of the incoming fluid, which 40 in turn will cause the expulsion of fluid from the opposite end of the cylinder through the connected outlet. The shifting of this last plunger will cause the valve portion thereof to change the connections to the cylinder for the first mentioned 45 plunger so that this in turn will be actuated, fluid being admitted at one end of the cylinder and 50 expelled from its opposite end through another outlet. As each plunger is a double acting piston, it is evident that the fluid can be divided into 55 portions which are twice the number of the

plungers and by increasing the number of plungers, any desired number of divisions may be made.

In detail, A is the casing formed of the integral casting having on one end thereof the internally threaded hollow boss B for connection with the inlet conduit C and also having upon opposite sides the internally threaded hollow bosses D, D', E, E' for connection with the outlet conduits F, F', F'', F''. G and H are cylindrical bores extending through the central portion of the casing intermediate the inlet and outlet connections, the opposite ends of which are closed by threaded plug caps I. J and K are double-headed piston plungers slidably fitting the bores G and H, these being of a length less than the length of the cylinder 15 between opposite end caps I so as to produce a predetermined displacement by the reciprocation thereof. Between the opposite ends of each of these plungers are grooves J', J'', J''' and K', K'', K''' which in certain positions of the plungers will 20 register with cooperating ports in the walls of the cylinders. These ports and connecting passages are preferably formed by intersecting bores, some of which enter from the outer surface of the casing and have their outer ends closed by plugs and 25 some of which enter through the hollow bosses D, D', E, E'. Thus as shown in dotted lines, Fig. 1, and also in the various cross sections thereof, there are a series of bores L extending radially at 30 different angles through each of the cylinders G and H and a series of longitudinal bores M intersecting with certain of said radial bores.

The arrangement of the different ports and passages is diagrammatically illustrated in Figs. 6 to 9 which also show the different positions of 35 the plungers J and K during the cycle. Thus in Fig. 6 both plungers J and K are at the lower ends of their respective cylinders in which position a radial bore C' connected with the inlet C and intersecting both cylinders G and H is in communication with the channels K'' and J'' of the respective plungers. In this same position a radial port G' in the cylinder G is also in communication with the channel J'' and this port is connected through the channel M' to the radial port H' at 40 the lower end of the cylinder H. In this same position the channel J''' in the plunger J communicates with a radial port G'' which is connected by the channel M'' with a radial port H'' 45 communicating with the upper end of the cylinder H. The channel J''' is also in communication with a radial port G''' which leads to the outlet F. Thus fluid entering from the conduit C can pass to the lower end of the cylinder H and its pressure 50 will cause the upward movement of the plunger 55

K which will displace fluid in the upper end of the cylinder H and expel it through the outlet F. Fig. 7 shows the position of the parts after the upward movement of the plunger K and it will be noted that in this position the channel K² is still in communication with the passage C' and also communicates with a radial port H³ connected by the passage M³ with a radial port G⁴ at the lower end of the cylinder G. The upper end of this cylinder is in communication with a radial port G⁵ connected by a channel M⁴ with a radial port H⁴ which is in communication with the channel K' in the plunger K. This channel K' also communicates with a radial port H⁵ leading to the outlet F'. Thus the fluid from the inlet C will pass to the lower end of the cylinder G, raising the piston J and expelling fluid from the upper end of the cylinder G to the outlet F'. Fig. 8 shows the position of parts after this movement in which the inlet C is still in communication through the passage C' with the channels K² and J². The channel J² is also in communication with a radial port G² which as before described is connected by the channel M² with the radial port H² at the upper end of the cylinder H. As before described, the lower end of the cylinder H communicates with the radial port H' connected by the channel M' with the radial port G', but this port G' is now in communication with the channel J' which also registers with the radial port G⁴ leading to the outlet F⁴. Thus fluid from the inlet C will pass to the upper end of the cylinder H forcing the plunger K downward and expelling fluid from the lower end of this cylinder H to the outlet F². Finally, in Fig. 9 the parts are in the position after the movement of the plunger K just described in which position the passage C' is in communication with a channel K² which registers with the radial port H⁴ connected by the passage M⁴ and radial port G⁵ with the upper end of the cylinder G. The lower end of this cylinder is also again connected through the radial port G⁴ and passage M³ to the radial port H³, but this port H³ is now in communication with the channel K³ which registers with the radial port H⁵ connected with the outlet F³. This permits of movement of the plunger J back into the position shown in Fig. 6 and during such movement the expulsion of fluid from the lower end of the cylinder G to the outlet F³.

It will be understood that during operation all of the ports and passages are filled with fluid but to avoid confusion we have indicated in the diagrammatic views only the fluid which is in motion. We have also used dash lines to indicate the propelling fluid and dots to indicate the fluid which is being expelled.

In order that the fluid may be divided into accurately measured portions, it is essential that each plunger should complete its full movement in its cylinder, and that the plunger which is stationary and acting as a valve should be locked against movement. This we have accomplished by an interlock which as shown comprises a pin N located in a radial bore L³ between the cylinders G and H. The plungers J and K are also provided with pairs of annular grooves J⁴, J⁵, K⁴, K⁵. These are so located that when the plunger is at one end of its movement, one of the grooves of the pair will register with the bore L³ and when the plunger is at the opposite end of its movement the other of said grooves will so register. The pin N is of such length as to be forced into the registering groove of the stationary plunger when displaced from the groove of

the moving plunger and thus during the entire movement of the latter it will serve as a lock for holding the stationary plunger from any movement. However, at the completion of travel of the moving plunger, the second groove of the pair will be registered with the pin N so as to permit of the locking of this plunger by the initial movement of the other plunger.

To facilitate manufacture, the casing A is provided with additional bosses through which bores are made and having their outer faces substantially perpendicular to the direction of the respective bores. These are shown in the several cross sections as follows: In Fig. 16 bosses O and O' are arranged for the entrance of bores L', L² respectively intersecting the cylinders G and H at angles of substantially 30° to the common plane of said cylinders. These bores form respectively the ports G⁴ and H' which intersect with the longitudinal bores M', M³. In Fig. 17 is shown a bore L³ in the common plane of the cylinders G and H and which as before described holds the pin N forming the interlock between pistons. In Fig. 18 the ports G² and H⁵ are bored respectively through the hollow bosses D and D' to connect the cylinders G and H with the outlets F² and F³. In Fig. 19 bores L⁴ and L⁵ respectively form the ports G⁴ and H⁴ connecting with the longitudinal bores M³ and M⁴. In Fig. 20 the bore C' enters from the hollow boss B to connect both cylinders G and H with the inlet C. In Fig. 21 the bore L⁶ in the common plane of the two cylinders forms the port G² which connects the cylinder G with the longitudinal bore M². Also, the bore L⁷ forms the port H³ which connects the cylinder H with the longitudinal bore M³. In Fig. 22 the ports G³ and H⁶ are bored through the hollow bosses E and E' to connect the cylinders G and H respectively with the outlets F and F'. In Fig. 23 bores L⁸ and L⁹ form the ports G⁵ and H² respectively connecting the cylinder G to the longitudinal bore M⁴ and the cylinder H to the longitudinal bore M². All of the radial bores which enter the casing from the outside thereof have their outer ends closed by screw plugs L¹⁰.

For convenience in mounting, the casing A is provided with a projection P on one side thereof which has a bore P' therethrough for engagement with any suitable supporting member.

While we have described specifically only two plungers operating in two cylinders, it is obvious that any number of cylinders and plungers, not less than two, can be used, the operation being essentially the same.

For certain uses it may be desirable to employ a plurality of dividing units used either in multiple or in series. Fig. 24 shows a series arrangement in which one unit Q has a liquid inlet Q' and a plurality of outlets Q². One of these outlets forms the inlet for a second unit R which also has a plurality of outlets R'. With this arrangement there will be a longer interval between successive discharges through the outlets R' than between successive discharges through the outlets Q² which may be advantageous for certain uses. For example, it will be seen that liquid will not be injected to the second unit until liquid is discharged from the outlet of the first device which is connected to the inlet of the second device. Or in other words, in the embodiment shown, liquid will be discharged from the second unit once every four times it is discharged from the first unit, and from the third unit once every sixteen times liquid is dis-

charged from the first unit, and so on for the remainder of the units. From the above it will be seen that the time rate of operation of successive units is governed by the operation of the 5 pistons of the preceding unit.

What we claim as our invention is:

1. Liquid dividing means comprising a plurality of units, each unit consisting of a casing having a fluid inlet and a plurality of fluid outlet passages, a plurality of cylinders and interconnecting passages and a reciprocating piston in each cylinder actuated by the incoming fluid and ejecting a measured quantity of outgoing fluid, and valve means operable by each piston for controlling and directing both the admission and ejection of fluid of another cylinder, one of said units being arranged in series with another unit and receiving its fluid from one of the outlets of the latter.

2. A multiple liquid dividing feed system comprising a first unit having an inlet and a plurality of outlets and having piston means operable by liquid delivered to said inlet under pressure for ejecting a measured quantity of liquid from first one and then another of its outlets, a second dividing unit having an inlet and a plurality of outlets and having piston means operable to eject a measured quantity of liquid from first one and then another of its outlets, conduit means connecting one of the outlets of said first-named unit with the inlet of said second-named unit so that liquid ejected from said one outlet operates to actuate the piston means of said second-named unit whereby the second unit is operated once every cycle of operation of said first-named unit.

3. A multiple liquid dividing feed system comprising a plurality of connected dividing units including a first unit having an inlet and a plurality of outlets and having piston means operable by liquid delivered to said inlet under pressure for ejecting a measured quantity of liquid from first one and then another of said outlets, each of the remainder of said units having an inlet and a plurality of outlets and having piston means operable by liquid injected into said units from said first unit to discharge a measured quantity of liquid first from one and then another of its outlets, and conduit means connecting said units.

4. A multiple liquid dividing feed system comprising a plurality of connected dividing units including a first unit having an inlet to which liquid is delivered under pressure from a source of supply and having a plurality of outlets from which liquid is ejected in sequence by piston means, each of the remainder of said units having an inlet and a plurality of outlets with pistons operable by injection of liquid from a preceding unit for ejecting a measured quantity of liquid in sequence from its outlets, and conduit means connecting an outlet of one of said units to an inlet of another of said units whereby the pistons of successive units will be actuated at a time period governed by the operation of the piston of the preceding unit.

5. In a liquid dividing means, a casing having a plurality of combined pumping and driving ele-

ments comprising two pairs of piston receiving cylinders and a piston in each cylinder, means connecting the pistons in each pair of cylinders for movement in unison, each of said elements having a conduit portion serving both as means for feeding liquid thereto to drive its piston and as means for discharging liquid therefrom, means to supply liquid to said conduit portions, valve means controlling the feeding of liquid to and the discharge of liquid from each of said conduit portions so that said pistons act sequentially as driving and as pumping means, and locking means external of said supply means and said conduit portions and cooperable with said elements to assure sequential operation of said 15 pistons.

6. In a liquid dividing means, a casing having a plurality of combined pumping and driving elements comprising two pairs of piston receiving cylinders and a piston in each cylinder, means connecting the pistons in each pair of cylinders for movement in unison, each of said elements having a conduit portion serving both as means for feeding liquid thereto to drive its piston and as means for discharging liquid therefrom, means 20 to supply liquid to said conduit portions, valve means controlling the feeding of liquid to and the discharge of liquid from each of said conduit portions so that said pistons act sequentially as driving and as pumping means, and locking 25 means external of said supply means and said conduit portions and operable by said pistons, said locking means acting to hold each pair of pistons alternately against driving movement during driving movement of the other pair of 30 pistons thereby to assure sequential operation of 35 said pistons.

7. In a liquid dividing means, a casing having a plurality of combined pumping and driving elements comprising two parallel pairs of piston receiving cylinders and a piston in each cylinder, means connecting the pistons in each pair of cylinders for movement in unison, each of said elements having a conduit portion serving both as means for feeding liquid thereto to drive its 40 piston and as means for discharging liquid therefrom, means to supply liquid to said conduit portions, valve means controlling the feeding of liquid to and the discharge of liquid from each of said conduit portions so that said pistons act 45 sequentially as driving and as pumping means, said casing having a guide bore joining one cylinder of one pair to one cylinder of the other pair, means closing said bore against flow of liquid therethrough, a locking pin reciprocally 50 fitting said bore and of such length that when one of its ends is flush with the surface of one cylinder bore its other end will project into the bore of said other cylinder, and a pair of longitudinally spaced locking grooves in each piston 55 of said one and of said other cylinder to receive said pin, said pin being alternately moved by one piston to engage in a groove in the other piston thereby to lock said pistons alternately against 60 movement.

ADOLF VON WANGENHEIM.
WALTER S. LANDON.
